US0D1104430S

(12) **United States Design Patent** (10) **Patent No.:** **US D1,104,430 S**
(45) **Date of Patent:** **** Dec. 9, 2025**

(54) **INSOLE**

(71) Applicant: **Yiqin Lin**, Guangdong (CN)

(72) Inventor: **Yiqin Lin**, Guangdong (CN)

(**) Term: **15 Years**

(21) Appl. No.: **29/999,429**

(22) Filed: **Apr. 16, 2025**

Related U.S. Application Data

(63) Continuation-in-part of application No. 29/801,816, filed on Jul. 30, 2021, now abandoned.

(51) **LOC (15) Cl.** **02-04**

(52) **U.S. Cl.**

USPC **D2/961**

(57) **CLAIM**

The ornamental design for an insole as shown and described.

DESCRIPTION

FIG. 1 is a top plan view of an insole showing my new design;

FIG. 2 is a bottom plan view thereof;

FIG. 3 is a left side elevational view thereof;

FIG. 4 is a right side elevational view thereof;

FIG. 5 is a back elevational view thereof; and,

FIG. 6 is a front elevational view thereof.

The broken lines shown in the drawings represent portions of the insole that form no part of the claimed design.

1 Claim, 6 Drawing Sheets
